UNITED STATES PATENT OFFICE.

CHARLES H. MARIE, OF MAYWOOD, NEW JERSEY.

CLIP FOR FOUNTAIN-PENS, PENCILS, AND THE LIKE.

1,125,144.

Specification of Letters Patent. Patented Jan. 19, 1915.

Application filed May 20, 1914. Serial No. 529,756.

To all whom it may concern:

Be it known that I, CHARLES H. MARIE, a citizen of the United States, and a resident of Maywood, in the county of Bergen and State of New Jersey, have invented certain new and useful Improvements in Clips for Fountain-Pens, Pencils, and the like, of which the following is a full and clear specification.

10 My invention relates to the construction and mounting of clips used in connection with fountain pens, pencils and similar articles for detachably securing them to the pocket of the wearer or to other articles. It 15 has already been proposed to form such clips of resilient sheet metal, wire and the like, bent into such form as to provide a yielding engagement of the retaining finger with the cloth of the pockets which slides 20 into engagement between the retaining finger and the body of the pen or the like. These members have been secured to the pen or the like in various ways such as by external spring bands and by integral tongues or 25 separate rivets which pass through perforations in the shell wall of the pen or the like.

The present improvements are in that type of holder or clip in which the retaining finger is secured in place by a member 30 which passes through the perforated shell wall or the like. It may be stated here that the invention is applicable to fountain pens, pencils and other articles to be carried in the pocket, but to illustrate the same I shall 35 refer to an embodiment thereof employed in connection with an adjustable feed pencil, which it will be understood, comprises a tubular shell or casing forming the main body of the pencil, a lead or other marking member longitudinally disposed therein and a feed mechanism for the marking member by 40 which the marking member is projected for use and may be withdrawn into the shell if desired, when not in use.

45 The objects of my invention are mainly to provide a quickly detachable clip, which is secure and practically rigid, so that it can not become disengaged by wear or use, and which presents a neat and pleasing appearance.

50 The invention is illustrated in the accompanying drawing, in which—

Figure 1 is a side elevation of an adjustable feed pencil with the clip attached thereto; Fig. 2 is a similar view with the face of the clip presented; Fig. 3 is a verti-

cal section through a portion of the pencil shell and clip, taken on the line 3—3 of Fig. 5; Fig. 4 is a vertical section through the pencil shell, showing the inner parts of the 60 clip in place, taken on the line 4—4 of Fig. 5; Fig. 5 is a transverse section on the line 5—5 of Fig. 3.

Referring more specifically to the drawings, 10 indicates the pencil shell and 11 the feed operating member therefor. The clip is illustrated as comprising the resilient retaining finger 12, which projects integrally from a body portion or base 13, which has inwardly curved ears 14, adapted to be inserted through suitable perforations in the pencil shell 10. A removable retaining plate 15 has a tongue portion 16 adapted to slide into firm frictional engagement with the ears 14, as illustrated in Figs. 2, 4 and 75 5, whereby the clip is positively and firmly secured in place on the pencil shell 10. The body portion 13 and the retaining plate 15 are suitably curved in conformity with the curvature of the pencil shell 10, so as to fit 80 snugly against the surface of the shell and not seriously obstruct the space within. The upper portion of the retaining plate 15 is wider than the tongue portion 16 so as to provide shoulders 17, which are arrested by 85 the ears 14 when the retaining plate has arrived at proper position within the grip of ears 14. A perforation 18 is formed in said head portion to facilitate removal of the retaining plate by a suitable tool when detaching the clip. To remove the clip from the cap of a fountain pen or the removable cap of a pencil, the tool may be inserted within the cap as the parts are readily accessible. In the case of pencils or the like in which 90 the clip is secured to the main shell, the pencil head must be removed to give access to the inside of the shell. It will thus be apparent that in all cases a damaged clip may 95 be replaced.

I claim:

1. The combination with a tubular shell having a perforated wall; of a clip having a base plate with rearward projections adapted to be inserted through the perforations of said wall, and a retaining member adapted to slidably engage said rearward projections for securing the clip to said wall.

2. The combination with a shell having 110 two laterally spaced longitudinally extending perforations in its wall; of a clip com-

prising a base plate with a longitudinally projecting resilient finger and inturned ears rearwardly projecting from the sides of said plate adapted to pass through said perforations, and a retaining plate adapted to be embraced by said inturned ears with the shell wall between it and said base plate.

2. The combination with a tubular shell having longitudinally extending lateral spaced perforations in its wall, of a clip having a transversely curved base plate with a resilient finger projecting from one

end and inturned ears projecting from the sides adapted to be inserted through the perforations in said shell wall, and a transversely curved retaining plate adapted to be slid into and out of engagement between said inturned ears with the shell wall between it and said base plate.

CHARLES H. MABIE.
